(57) **CLAIM**

We claim the ornamental design for a universal remote controller, as shown and described.

DESCRIPTION

FIG. 1 is a perspective view of a universal remote controller showing our new design;

FIG. 2 is a bottom side view thereof;

FIG. 3 is a top view thereof;

FIG. 4 is a rear side view thereof;

FIG. 5 is a front view thereof;

FIG. 6 is a left side view thereof; and,

FIG. 7 is a right side view thereof.

The broken lines in the figures depict regions of the universal remote controller that form no part of the claimed design.
